ATTY

UNITED STATES PATENT OFFICE.

OSCAR G. THOMAS, OF TAUNTON, MASSACHUSETTS.

DESIGN FOR A STOVE OR RANGE.

SPECIFICATION forming part of Design No. 21,851, dated September 6, 1892.

Application filed July 28, 1892. Serial No. 441,537. Term of patent 7 years.

To all whom it may concern:

Be it known that I, OSCAR G. THOMAS, a citizen of the United States, residing at Taunton, in the county of Bristol and State of Massachusetts, have invented and produced a new and original Design for a Stove or Range, of which the following, taken in connection with the accompanying drawing, is a specification.

The illustration is a perspective representation of a range the base of which embodies my design.

The leading feature of my design is a broad band or surface surrounding the base and ornamented with a succession of feathered scrolls, like young ferns, inclined in opposite directions toward the center of each side of the base, where a center-piece harmonizing with said ornamentation is introduced. A

somewhat similar ornament inverted is shown at the corners of the base. Below this ornamented band is a plain ogee-band, and below this the legs at the corners. The ornamentation of the other portions of the range forms no part of my present design.

I claim as my invention—

The design for a stove or range, substantially as shown and described.

In testimony whereof I have signed my name to this specification, in the presence of two subscribing witnesses, on this 21st day of April, A. D. 1892.

OSCAR G. THOMAS.

Witnesses:

A. H. SPENCER,
THOS. J. KENNY.
